UNITED STATES PATENT OFFICE.

JOHN T. CROWLEY, OF BEACON FALLS, CONNECTICUT, ASSIGNOR TO THE BEACON FALLS RUBBER SHOE COMPANY, OF BEACON FALLS, CONNECTICUT, A CORPORATION OF CONNECTICUT.

RUBBER SHOE.

1,047,504.

Specification of Letters Patent. Patented Dec. 17, 1912.

Application filed May 22, 1912. Serial No. 693,926.

To all whom it may concern:

Be it known that I, JOHN T. CROWLEY, a citizen of the United States, residing at Beacon Falls, in the county of New Haven and State of Connecticut, have invented 5 certain new and useful Improvements in Rubber Shoes, of which the following is a specification.

My invention relates to rubber shoes, and 10 has for its object to improve the construction of heels for such shoes.

In the use of rubber shoes it is the familiar experience that the said shoes are apt to be destroyed at the heel, particularly at the 15 lower part thereof, before the remainder of the shoe is worn out.

The particular object of my invention therefore is to protect and strengthen the shoe at such parts as are most subject to 20 wear.

My invention consists in the provision of a cushion inside of the said heel and which overlies the sole thereof, which protects the rubber forming the sole of said heel from 25 the action of the shoes and particularly from the action of projecting nails in said heels, and which as illustrated is made of a plurality of plies of fabric and interposed sheets of rubber.

30 The drawing is a longitudinal section of a rubber shoe having my invention applied thereto.

My invention is illustrated as applied to a rubber shoe A of ordinary construction, 35 having as usual a fabric lining B which extends throughout the interior of the shoe on which is secured a rubber body C.

The bottom or sole of the heel F has in accordance with my invention a cushion 40 formed therein of protecting and resilient material. This cushion, which as a whole is lettered G, is formed by preference of a plurality of layers of textile fabric of which three are illustrated and which are lettered 45 g, g¹, g². The said layers of fabric preferably have a sheet or layer g³ of rubber interposed between each of the fabric layers and the fabric and rubber are secured together, as by being vulcanized, the vulcanization 50 being conveniently carried out at the same time that the other parts of the shoe are

subjected to the process of vulcanization. The said cushion G extends from side to side of the heel, and from front to rear thereof, and overlies the sole of the heel F 55 and may be covered by the inner lining B of the shoe. It frequently happens that the leather shoes which the rubbers protect have projecting nails in their heels which quickly wear through the rubber. Frequently also 60 these heels are irregular in shape resulting from being worn down excessively at the rear portion thereof, providing a space into which the rear part of the shoe may pass and be compressed therein in walking, 65 wrinkling and breaking the same and leading to the early destruction of the rubber shoe at this point. My improved cushion G strengthens the heel as to the sole thereof, and therefore enables the same to resist the 70 entrance of the nails in the heel. It likewise increases the resistance of the sole of the heel to wrinkling, and increases the wear of the heel at this point.

I claim as my invention:—

1. A heel for rubber shoes comprising an outer sheet of rubber forming the sole of the heel, a plurality of layers of fabric of substantially the area of the inside of the heel overlying said sole and forming a 80 cushion and protection therefor, and layers of rubber between said layers of fabric, said layers of fabric and rubber being secured together.

2. A heel for rubber shoes comprising an outer sheet of rubber forming the sole of the heel, a plurality of layers of fabric of substantially the area of the inside of the heel overlying said sole and forming a cushion and protection therefor, and layers of rubber between said layers of fabric, said layers of fabric and rubber being secured together, and an inner sole lining lying over said rubber and fabric cushion.

In witness whereof, I have hereunto 95 signed my name in the presence of two subscribing witnesses.

JOHN T. CROWLEY.
